US00D707884S

(12) **United States Design Patent**
Park

(10) **Patent No.:** **US D707,884 S**
(45) **Date of Patent:** **** Jun. 24, 2014**

(54) **VIBRATION PUFF**

(75) Inventor: **Youn Hoon Park**, Yongin (KR)

(73) Assignee: **Eyesel Creative Co., Ltd.**, Seoul (KR)

(**) Term: **14 Years**

(21) Appl. No.: **29/427,081**

(22) Filed: **Jul. 13, 2012**

(30) **Foreign Application Priority Data**

Jan. 27, 2012 (KR) 30-2012-0003945

(51) **LOC (10) Cl.** **28-02**

(52) **U.S. Cl.**

USPC **D28/7**

(58) **Field of Classification Search**

USPC D28/7, 8, 20-22, 30-31, 76, 85, 99;
132/108, 202, 208, 317.32;
401/202-207, 261-267; D4/132-135;
D24/119
